SHOE STRUCTURE

Chester F. Rohn and Franklyn A. Rohn, Milwaukee, Wis.

Application October 4, 1935, Serial No. 43,546

1 Claim. (Cl. 36—71)

The present invention relates in general to improvements in the art of manufacture of foot wear, and relates more specifically to improvements in the construction of shoes having arch bracing or supporting means built therein.

Generally defined, an object of the present invention is to provide an improved shoe structure wherein the instep or arch portion of the wearer's foot is effectively braced or supported. Numerous types of instep or arch supports have heretofore been proposed. In one type of these previous arch supports, the insole is provided with an integral side flap which, during lasting of the shoe, is bent upwardly and finally either confined between the adjacent side of the vamp and inner lining, or permitted to lie exposed against the inner surface of the lining. This type of construction has the disadvantages of requiring a large and wasteful piece of leather in the formation of the insole with a flap; and if the leather flap which forms the arch support is finally disposed between the outer leather and the lining it is not visible in the completed shoe for sales purposes, whereas location of the flap in visible position within the shoe necessitates cementing and frequently produces curling and distortion of the support, thereby causing annoyance to the wearer. In order to obviate the high cost of insole construction and the waste of leather due to such integral insole and flap formation, it has also been proposed to form the insole and arch support as separate pieces and to sew or otherwise attach the flap either to the inseam ridge or to the edge of the insole prior to the lasting operation. These modified types of arch supporting flaps were also disposed either within or at the outside of the inner lining, and while they do result in reduction in cost of construction, they are also objectionable for the several other reasons above noted. It has moreover been proposed to utilize a separate arch support initially inserted between the outer leather and the lining, and subsequently attached to the insole and welt, during the lasting operation, but this type of structure likewise fails to reveal the fact that the completed shoe has an arch brace embodied therein, so that all of the prior arch supporting structures are relatively objectionable for one reason or another.

It is therefore a specific object of the present invention to provide an improved arch brace for shoes or the like, wherein the bracing flap is confined within a pocket which is visible from within the completed shoe but which cannot annoy the wearer, the brace being either attached to or detached from the insole.

Another specific object of the invention is to provide an instep support which may be formed of any suitable bracing material, including leather but not necessarily so, which need not be directly attached to the insole either prior or subsequent to the lasting operation.

A further specific object of the invention is to provide a durable and effective arch supporting structure which can be readily applied to various styles and types of foot wear at slight additional cost.

Still another specific object of the invention is to provide a new and useful arch brace for welt shoes, which can be embodied in a shoe assembly without unusual difficulty, and without complicating the attachment of the vamp lining and welt to the inseam ridge of the insole.

These and other objects and advantages of the present invention will be apparent from the following detailed description.

A clear conception of several embodiments of the present improvement, and of the mode of constructing shoes having the new arch brace applied therein, may be had by referring to the drawing accompanying and forming a part of this specification wherein like reference characters designate the same or similar parts in the various views.

Fig. 1 is a central longitudinal section through a man's shoe of the welt type, showing a portion of the inner pocket which normally confines the arch brace, broken away to reveal the brace;

Fig. 2 is a transverse section through the instep portion of the shoe shown in Fig. 1, the section having been taken along the line 2—2;

Fig. 3 is a similar section through a modified shoe structure; and

Fig. 4 is an internal plan view of the upper shoe structure before lasting.

While the invention has been illustrated herein as being applied to a man's shoe of a particular type, it is not intended to thereby restrict the scope, since the improvement is obviously more generally applicable to men's high shoes or to women's and children's shoes of all types having either nailed, sewed or cemented soles.

Referring to the drawing, the improved shoe structure shown in Figs. 1 and 2 has been formed from an upper structure of the type shown in Fig. 4, and comprises in general an upper composed of outer leather 6 and having a lining 7 and suitable reinforcements interposed between these parts; an insole 8 having a continuous inseam

ridge 9 normally projecting downwardly therefrom; a partial or a continuous welt 10 secured to the leather 6, lining 7 and inseam ridge 9 by means of inseam stitching 11; an outsole 12 secured to the welt 10 in any suitable or desirable manner; cushioning or filling means disposed between the insole 8 and outsole 12 within the inseam ridge 9; and heel structure secured to the rear portion of the outsole 12 in any suitable manner.

As shown in Fig. 4, the outer leather 6 of the vamp is composed of a forepart which may or may not be provided with a separate tip, and two rear quarters 13 sewed together and to the side and rear edges of the forepart and having lacing eyelets 14 associated therewith. The lining 7 is composed of a cloth vamp lining, and leather quarter linings 15 sewed together and to the forepart lining; and the assembled lining 15 20 25 30 35 40 45 50 55 60 65 70 75 80 85 90 95 to limit the invention to the exact details of construction and to the precise mode of manufacture, herein shown and described, for various modifications within the scope of the appended claim may 5 occur to persons skilled in the art.

We claim:—

In a shoe, upper structure comprising outer 10 leather and an inner lining loosely engaging the interior of said leather at the arch portion of the shoe, a pocket pad visible from within the shoe and being secured along its upper edge to the interior of said lining to form a substantially semi-

circular pocket at said arch portion, a relatively stiff bracing pad having a substantially semi-circular skived upper edge portion loosely confined and freely movable within said pocket between said lining and pad and having a lower substantially straight edge at the open end of said pocket, an insole having an inseam ridge, a welt, and common securing means for fastening said welt, said outer material, said lining, and said pocket to said inseam ridge. 5
